UNITED STATES PATENT OFFICE

2,147,536

RETRACTABLE LANDING GEAR FOR
AIRPLANES

René Lucien Lévy, Montrouge (Seine), France,
assignor to Société d'Inventions Aeronautiques
et Mécaniques S. I. A. M., Fribourg, Switzer-
land

Application November 9, 1937, Serial No. 173,693
In France November 10, 1936

1 Claim. (Cl. 60—52)

The present invention relates to the systems of retractable landing gear for airplanes, in which the action of a hydro-pneumatic energy accumulator is utilized for lowering the landing gear.

The invention is applicable, in particular, to systems of this type which include a hydraulic locking device and, inter alia, to the systems of retractable landing gear for airplanes which are described in applicant's prior Patent No. 2,001,620.

The invention consists in providing the systems of airplane landing gear which utilize the action of a hydro-pneumatic energy accumulator for lowering the landing gear, with an auxiliary safety device adapted to be brought into operation to ensure the descent of the landing gear when the energy accumulated in the hydro-pneumatic accumulator ceases accidentally to be available for that purpose, for example, in the event of a fracture in the pipe connecting said accumulator with the jack.

A combination of this auxiliary safety device with the system described in the specification of said prior patent is represented diagrammatically, in the accompanying drawing which shows the essential components of the earlier system, that is to say:

A pump 1 which draws its supply from a tank 2, a jack V for actuating the landing gear (not shown), a hydro-pneumatic accumulator 9 communicating with the jack V by way of a hydraulic locking device 8 which is connected, through a pipe 3a, with the delivery pipe 3 between the pump 1 and the jack V; a non-return valve 4 in said pipe 3, and, finally, an exhaust valve 6 provided in a pipe 5 branching from the delivery pipe 3.

According to the present invention a branch 3d, from the delivery pipe 3 of the pump 1, is adapted to place said pump in communication with the chamber v' on the accumulator side of the jack V, when the cock r' provided on said pipe 3d, is opened. Between the branching-off point a and the chamber v' of the jack V is a second cock r².

The system arranged in this manner functions as follows:

Normally, the cock r¹ is closed, and the cock r² is open.

In order to raise the landing gear, the exhaust

valve 6 being closed, the pump 1 is started. As pointed out in the specification of said prior patent, the lifting pressure acting in the pipes 3 and 3a forces the piston of the jack V upwards (in the case shown in the drawing), the effect of which is to increase the pressure in the accumulator 9, the hydraulic locking device 8 then allowing liquid to pass from the chamber v' into the accumulator 9 as explained in said prior patent.

For the normal lowering of the landing gear, all that is needed is for the pilot to open the valve 6, so that the action of the accumulator and the gravity causes the piston of the jack V to descend.

If, for example, a fracture should occur in the pipe 3c, or the accumulator 9 should, for any reason, be unable to function, the pilot opens the cock r', closes the cock r² and starts the pump 1 whilst actuating the exhaust valve 6. In these circumstances, liquid under pressure is delivered into the chamber v' of the jack V opening the valve c, so that the motive action of the pump 1 supplements gravity in order to cause the landing gear to descend.

It will be understood that this safety device is applicable to all systems of landing gear in which the action of a hydro-pneumatic accumulator is put into operation for the descent of said gear, whether said systems be, or be not provided with a hydraulic locking device similar to the device 8, the function of which has been described in the specification of said prior patent.

I claim:

Actuating system for retractable landing gear for airplanes comprising: a motive fluid pump, a hydraulic jack or the like, a pipe for normal operation between said pump and one of the chambers of the jack, a hydro-pneumatic accumulator, a pipe between the other chamber of said jack and said accumulator, a safety pipe branching off from said normal operation pipe and connecting the pump to the other chamber of the jack, means for normally placing said safety pipe out of the circuit of the pump, means for bringing said safety pipe into operation, and an exhaust pipe branching off from the normal operation pipe.

RENE LUCIEN LEVY.
